ATTORNEYS

UNITED STATES PATENT OFFICE.

ADOLPH MOHRBACHER, OF CRIPPLE CREEK, COLORADO.

ADJUSTABLE DRILL-SUPPORT.

No. 857,529.

Specification of Letters Patent.

Patented June 18, 1907.

Application filed August 28, 1906. Serial No. 332,346.

To all whom it may concern:

Be it known that I, ADOLPH MOHRBACHER, a citizen of the United States, and a resident of Cripple Creek, in the county of Teller and State of Colorado, have made certain new and useful Improvements in Adjustable Drill-Supports, of which the following is a specification.

My invention is an improvement in drills and relates particularly to the means for supporting what are commonly known as hand machine air drills; and the invention consists in certain novel constructions and combinations of parts as will be hereinafter described and claimed.

In the drawing, Figure 1 is a side elevation of a support embodying my invention held between two opposite walls. Fig. 2 is a vertical longitudinal section of the support in connection with an air drill, the latter extending between the support and the upper wall. Fig. 3 is a cross section on about line 3—3 of Fig. 2. Fig. 4 is a cross section on about line 4—4 of Fig. 2, and Fig. 5 shows a different form of point from that illustrated in Fig. 2.

My invention seeks to provide in connection with an adjustable or extensible cross bar, a support for the stopping bar of an air drill, such for instance as the Iler, Ingersoll Jap, Murphy, Hartsock, Shaw Eclipse, and similar well known machines that are made with self-air feeding stopping bars, the machines being operated by compressed air as is well understood by those skilled in the art.

In the drawing I represent at A an Iler air machine, in which the air pipe A' leads to a cylinder A² and the stopping bar A³ works in the cylinder A² and is formed at its lower end to fit in any desired one of a series of sockets B' formed in the adjustable sleeve B presently described.

The extension cross bar comprises the outer or tubular section C and the inner or bolt section D, the latter being threaded in the section C and pointed at one end D' and provided near such end with openings D² forming sockets for a jack bar whereby the threaded section D may be turned to adjust the length of the sectional cross bar. At its outer end, the tube C is provided with a threaded bearing for the screw stem E' of the point E, such threaded bearing being preferably provided in a separate sleeve E² and fitted and secured within the end of the tube C as shown in Fig. 2. The point E may be as

shown in Fig. 2, or it may be preferred in some instances to use a different form of point such as shown at e in Fig. 5. At its end opposite the sleeve E², the tube C is provided with a threaded bearing for the bolt D, such threaded bearing being formed in a separate sleeve F suitably threaded and fitted and secured within the end of the tube C as shown in Fig. 2.

The bolt D is threaded to fit the sleeve F, and is provided at its inner end with a slide G fitting within the tube C and operating to steady the movement of the inner end of the bolt D within the tube C, as will be understood from Fig. 2, and also to form a stop, which, by contact with sleeve F, prevents the bolt D from being drawn out of tube C. This slide G is preferably in the form of a collar screwed on a screw stem g at the inner end of the bolt D so it can be applied after the bolt has been screwed through its sleeve F. Thus in applying the parts, it will be understood that the sleeve F may be fitted within the tube C at one end, the bolt D be screwed into said sleeve F and project at its inner end within the tube C, the slide G be then applied, and the sleeve E² finally applied to receive the point E or e as will be understood from Fig. 2.

The sleeve B is fitted over the tube of the extension bar, being provided at one end with an inwardly projecting flange B² to fit and slide along the bolt D and thus steady and brace such end of the sleeve B as best shown in Fig. 2. This sleeve it will be noticed is movable along the extension bar in a longitudinal direction, and also may be turned on said bar, and means are provided for securing the sleeve in any desired longitudinal or rotary adjustment upon the cross bar. This may be simply a clamping screw H as shown, or it may be any other suitable form of clamp. The screw H is preferred because of its simplicity and the ease with which it may be operated to secure and release the sleeve.

By my invention it will be noticed the air machine A can be used for stopping, drifting, etc., or at any angle desired, as the jacket or sleeve B may be adjusted to any suitable position upon its supporting bar, and by means of its said adjustments, almost any one of the sockets in the said sleeve or jacket may be brought into position to support the drill by receiving the lower end of the self-feeding stopping bar as will be understood from Fig.

2. The sockets, it will be noticed, form seats for the stoping bar which may be simply dropped at its lower end into any desired socket and the air be supplied to operate the 5 drill and to also secure the self-feeding by the action of the air in the cylinder A² upon the stoping bar as is well known by those skilled in the art. It will be noticed therefore that my invention provides a support 10 for air machine drills, operated by self-feeding stoping bars, and that the drill A shown is one form of many such drills now in use.

The support may be made in different sizes to suit different demands, and when 15 operated will result in the saving of much time and labor by permitting the convenient setting up of the machine without requiring the cutting of hitches, and dispensing with the use of wedges, etc., as are commonly used 20 providing supports for drills of the character described. It will be understood that in practice, the extension cross bars may be manufactured and sold to those using such drills.

25 It will be understood that the sleeve or jacket B is an important feature of my invention, as it provides in connection with a cross bar an adjustable support providing a seat for the stoping bar as before described.

30 I claim:

1. An extension cross bar consisting of a tubular section, sleeves threaded internally

and fitted and held within the opposite ends of the said tube, a point having a screw stem threaded into one of said sleeves, and a bolt 35 section threaded into the other sleeve and having at its inner end a screw stem and a collar thereon and forming a slide fitting within the tubular section, said bolt having a point at its outer end, and an adjustable 40 sleeve or jacket fitting on and movable longitudinally and rotarily upon the tube of the cross bar, and having at one end an inwardly projecting flange fitting and slideable along the threaded bolt, the said sleeve or jacket 45 being provided with a socket or sockets to receive the end of a stoping bar, and means for securing the said sleeve or jacket in any desired adjustment, substantially as set forth.

2. A cross bar having a tubular section 50 and a bolt or threaded section screwing into the tubular section, and a sleeve or jacket adjustable upon the tubular section and projecting at one end over the bolt section and having at said end an inwardly projecting flange to slide upon the bolt section, and steady such end of the sleeve or jacket, the latter having a seat or seats for a stoping bar, substantially as set forth.

ADOLPH MOHRBACHER.
